OF NEWARK, NEW JERSEY, A CORPORATION OF DELAWARE

PAD HOLDER AND ADJUSTABLE CLAMP

Application filed June 29, 1928. Serial No. 289,216.

This invention relates to holders and means for retaining paper sheets thereon. Devices of this character are a necessary convenience where numerous thin sheets of material are to be held in orderly arrangement, such for instance as papers, either loose and unconfined or connected in pad form, such as calendars, memorandum pads, lists, bills, etc., but as such sheets are usually subject to change in number, and consequently their combined thickness, by addition of new sheets and removal of those which have been used or become obsolete,—as in the case of a calendar,—provision should be made to adjust the clamping means to accommodate such varying conditions.

One of the objects of the present invention is to provide means whereby a spring clamping device may be conveniently raised and lowered relative to the plate support on which the sheets rest, so that a few sheets may be held as firmly as a far greater number.

A further feature is in the provision of a pad support possessing unusual merit in its design and structure whereby strength, economy in material and neatness in appearance are secured.

These important objects are accomplished by the novel design, arrangement and combination of parts, hereinafter described and illustrated in the accompanying drawing, forming an essential portion of this disclosure, and in which:

Figure 1 is a perspective view looking from the outer side and rear end of a pad support as made in accordance with the invention, showing its application to a thick pad.

Figure 2 is an enlarged, partial longitudinal sectional view of the same.

Figure 3 is a view showing the several details of construction in perspective and in the relation they will assume when assembled.

A flat sheet metal sub-base plate, generally designated by the numeral 10, cut in the shape of an oblong rectangle or otherwise to suit its purpose, has formed near one end, in its under side, a shallow transverse raised panel 11, in the end portions of which are sheared prongs 12 extending rearwardly at right angles, and containing end slots 11'.

Fitting the panel 11, and level with the under surface of the sub-base plate 10, is a plate 13 having depressions 14 suited to receive the prongs 12, which are entered through openings 15 at the outer ends of the depressions 14 and are afterwards turned and upset to fill the same smoothly, holding the plates rigidly in fixed relation.

Integral with the ends of the plate 13 are outstanding right angular brackets 16, their rear edges extending outwardly beyond the corresponding edge of the plate, and formed in the brackets, adjacent their rear edges, are longitudinal slots 17, straight at the back and having in their front edges a series of slightly undercut notches 17^a—17^b—17^c.

Spaced parallel from the slots, in the front portion of the brackets are similar slots 18, having straight, forwardly extending notches 18^a—18^b—18^c, and directly opposite the notch 18^b, in the rear edge of the slot is an inreaching ledge 19.

An upper base plate 20 is shaped in contour to the sub-base 10, upon which its depressed margin 21 is seated, the inturned edges 22 of a felt fabric intervening, this fabric enveloping the edges of the sub-base 10 and extending completely over its entire outer area, constituting a cushion surface 23 to prevent abrasion of whatever the pad support may rest upon.

The plate 20 has narrow longitudinal slots 24 neatly fitting the brackets 16 which are first passed through the slots 11' in the plate 10, thence the slots 24, the plate 20 being rigidly held to the sub-base plate 10 by rivets 25 passed through openings 26 in the plate 20 and corresponding openings 27 in the plate 10, these latter openings being formed in raised nipples 28 in the plate, these openings receiving the rivet heads so that no projection interferes with the felt cushion 23.

The paper pad X is pressed against the level surface of the plate 20 by a clamping member 30, preferably curved convexly to present spaced contacting edges disposed longitudinally in the direction of the length of the pad, the clamping members being integral with an angular down-reaching plate connection 31 leading to a flat table 32.

Reaching rearwardly from the element 32 are wings 33, their upper, downwardly inclined upper edges having reentrantly turned, inbent hooks 34, and in their semi-circularly curved ends are openings 35.

Another sheet metal frame member 36 is curled to produce a tube 37 at one of its edges, suited to fit between the brackets 16 and headed pins 38 tightly driven into the tube ends 10 after passing through the slots 17 in which the pins are freely movable.

The opposite edge of the member 36 is curled outwardly to form a guard 39, further on explained, and extending forwardly from 15 the ends of the member 36 are plate levers 40 engageable closely adjacent within the wings 33 and containing openings 41 registrable with the wing openings 35.

A tube 42 is held in alinement with the 20 openings 35-41 by headed pins 43 passing through the slots 18, and wing and lever elements, to be tightly forced into the tube ends acting as pivots for the clamping member elements 30 to 34.

25 A double spring 44 is coiled about the tube 42, its looped portion 45 extending upwardly to engage the tube 37 and its lower, forwardly projecting ends 46 arranged to forcibly impinge on the element 31, causing the clamping member 30 to press firmly on papers X.

When the clamping member and its unitary members have pivoted on the pins 43 until the levers 40 engage the loops 34, further clamping effect is arrested and it becomes desirable to move the pivots 43 and 38 from the outer notches 18^c and 17^c to the intermediate notches 18^b and 17^b, and ultimately to the lowermost notches 18^a and 17^a in order to maintain a substantially uniform pressure 40 on the sheets remaining on the plate 20.

Shifting of the pivots is readily accomplished by drawing the same outwardly into the slots 18 and 17 respectively and transferring to the other notches as required, and 45 it will be noted that the shape of the rear notches is such as to prevent inadvertent movement, which is also guarded against by the projections 19.

Obviously the clamping member 30 is released by applying sufficient pressure to overcome the tension of the spring elements in the usual manner.

From the foregoing it will be seen that a simple device for this purpose has been disclosed in the preferred form of its embodiment, but it is not desired to restrict the details to the exact construction shown, it being obvious that changes, not involving the exercises of invention, may be made without 60 conflicting with the scope of the appended claims.

Having thus described the invention, what is claimed as new and desired to secure by Letters Patent, is:—

65 1. A pad holder having a surface to re-

ceive a pad, a spring actuated clamping member to press the pad against the surface, an adjusting member on said surface, and means removably secured to said clamping member to adjustably position said clamping member 70 in said adjusting member relatively to said surface.

2. A pad holder having a surface to receive a pad, a spring actuated clamping member to press the pad against the surface, 75 means to arrest the action of said clamping member at a definite stage in its movement, and means for raising and lowering said clamping member by stages with respect to said surface.

3. A pad holder comprising a pad support, brackets at one end of said support having pairs of stepped notches, a spring impelled clamping member to confine a pad upon the support, and means removably secured to said clamping member for securing said clamping member in any of the pairs of notches selectively.

4. A pad holder comprising a pad support, brackets on said support provided with pairs 90 of spaced parallel slots and notches in the edges of the slots, a frame, a clamping member carried by said frame, pivots secured to said frame slideable in said slots and selectively engageable in said notches to position said frame and clamping member relatively to said pad support, and means on said frame to actuate said clamping member.

5. A pad holder comprising a pad support, brackets on said support having pairs of 100 spaced parallel slots and notches in the edges of the slots, a clamping member, a frame to which said clamping member is pivoted, springs combined with said frame to urge said clamping member against the pad on the support, means cooperating between said clamping member and frame to limit the movement of said clamping member, and means fixed in said frame and movable in the slots of said brackets engageable selectively 105 in the notches thereof to position the clamping member relatively to said pad.

6. A pad holder comprising a base plate having a raised panel, a plate fitting said panel, interlocking means cooperating between said panel and plate, slotted brackets integral at the ends of said plate, a support plate through which said brackets extend, the base and support plates being riveted together, a clamping member for the pad, and means for adjusting said clamping member in the slots of said bracket.

7. A pad holder comprising a base plate having a raised panel, a plate fitting said panel, interlocking means cooperating between said panel and plate, slotted brackets integral at the ends of said plate, a support plate through which said brackets extend, the base and support plates being riveted together, a felt sheet below said base plate, the 125

edges of the felt sheet being interposedly clamped between the edges of said plate, a spring actuated clamping member to retain a pad on said support plate, and means in the 5 slots of said brackets to adjust the operative height of said clamping member relative to said support plate.

This specification signed this 28th day of June, 1928.
